[57] **CLAIM**

The ornamental design for a combined gripping, crimping, cutting and wire stripping tool, as shown and described.

DESCRIPTION

FIG. 1 is a front elevational view of a combined gripping, crimping, cutting and wire stripping tool showing my new design;

FIG. 2 is a top plan view thereof;

FIG. 3 is a left side elevational view thereof;

FIG. 4 is a fragmentary rear elevational view thereof, showing the jaw portion; and,

FIG. 5 is a right side elevational view thereof.

FIG. 1

FIG. 2

FIG. 3

FIG. 4

FIG. 5
